US0D1067137S

(12) **United States Design Patent** (10) Patent No.: **US D1,067,137 S**
Oh (45) Date of Patent: ** Mar. 18, 2025

- (54) **VEHICLE REAR LOWER FASCIA**
- (71) Applicant: **GM GLOBAL TECHNOLOGY OPERATIONS LLC**, Detroit, MI (US)
- (72) Inventor: **Zooyoung Oh**, Incheon (KR)
- (73) Assignee: **GM GLOBAL TECHNOLOGY OPERATIONS LLC**, Detroit, MI (US)
- (**) Term: **15 Years**
- (21) Appl. No.: **29/898,153**
- (22) Filed: **Jul. 24, 2023**
- (51) LOC (15) Cl. **12-16**
- (52) U.S. Cl. **USPC D12/169**
- (58) **Field of Classification Search**

Primary Examiner — Philip S Hyder

Assistant Examiner — Beena Patel

(57) **CLAIM**

The ornamental design for a vehicle rear lower fascia, as shown and described.

DESCRIPTION

FIG. 1 is a front and left side perspective view of a vehicle rear lower fascia showing my new design;

FIG. 2 is a front elevation view of the vehicle rear lower fascia of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle rear lower fascia that form no part of the claimed design.

1 Claim, 7 Drawing Sheets
